UNITED STATES PATENT OFFICE.

JOHN J. REHALLY, OF NEW YORK, N. Y.

DIGGING-BUCKET.

1,217,500.

Specification of Letters Patent. Patented Feb. 27, 1917.

Application filed May 26, 1915. Serial No. 30,495.

To all whom it may concern:

Be it known that I, JOHN J. REHALLY, a subject of the King of Great Britain, having declared my intention of becoming a citizen of the United States, residing in New York city, borough of Manhattan, county of New York, and State of New York, have invented certain new and useful Improvements in Digging-Buckets, of which the following is a specification.

My invention relates to new and useful improvements in digging buckets employed in excavating operations, and more particularly of the types provided with a wall having a digging edge to cut or break into the material to be excavated or lifted and transferred by the bucket. The primary object of the invention is to provide a bucket which will be simple in construction and in which the digging wall will be of improved construction, particularly as regards the construction and arrangement of the teeth which engage the material to be excavated or hoisted, and which will be of great strength and durability. A further object is to provide improved means for connecting the teeth to the bucket wall whereby said teeth will be rigidly and firmly held in position during the operation of the bucket, but may be readily interchanged when the replacement or repair of the teeth is required. A further object is to provide a digging wall of the bucket with means for securing the teeth thereto which will be so constructed that clogging of the teeth will be obviated.

A further and important object is to so construct and design the front or digging wall of the bucket that it may be readily cast from suitable metal and when cast will be ready for use without additional milling or machine work.

Another object is to provide a front or digging wall which will be adapted for use with various types and forms of teeth now available on the market, whether said teeth are of one or more parts.

The invention consists in the improvements to be more fully described hereinafter, and the novelty of which will be particularly pointed out and distinctly claimed.

I have fully and clearly illustrated my invention in the accompanying drawings to

be taken as a part of this specification, and wherein—

Figure 1 is a view in side elevation of one type of digging bucket constructed in accordance with my invention.

Fig. 2 is a view partially in front elevation and partially in cross-section of the bucket shown in Fig. 1, the broken away portion being on the line 2—2, Fig. 6,

Fig. 3 is a section on the line 3—3 of Fig. 2,

Fig. 4 is a disassembled perspective view of a portion of the bucket bottom or digging wall and one of the teeth, the latter being in position to be attached to the bucket wall,

Fig. 5 is a front view of the front or digging wall with one tooth removed, and

Fig. 6 is a rear view of the front or digging wall with one tooth removed.

Referring to the drawings by characters of reference, 1 designates generally a bucket body of the character or type employed in connection with a beam 2 adapted to be carried by the swinging boom of an excavating machine of well-known type (not shown). As my invention is applicable generally to buckets of this type without regard to the specific construction thereof, I do not deem it necessary to enter into a specific description of the construction of such bucket. It is sufficient to state that it may consist of side walls 3, 4, a rear wall 5, and a front or digging wall 6, the front of the bucket being open to permit the material excavated to enter the body of the bucket, and the rear of the bucket being adapted to be closed by a movable bottom wall 7 hinged to the bucket body, as at 8, said movable wall being constructed to close the bottom of the bucket during the digging and carrying operation and to be opened at the point of discharge to permit the contents of the bucket to be discharged through the bottom of the bucket. The front wall 6 of the bucket 1 is curved transversely as shown in Fig. 2, the side edges of said wall being riveted or otherwise suitably secured to the side walls 3 and 4. This wall 6 is provided at its forward portion with a cutting or digging edge 9, which is adapted to cut or bite into the material being excavated, in the case of loose material, or to be forced under solid ma-

terial, such as rock, to cause the material to enter the open end of the bucket. It is the experience in the operation of such buckets that the greatest wear and tear is exerted upon this front or digging wall as it is the one which either forcibly engages or is engaged by the material when the bucket is being filled, and it is one of the important purposes of my invention to provide a front wall which will be extremely rigid and strong so as to withstand this wear and tear. I preferably make the front wall of cast metal, for instance, manganese steel, cast to the desired form, and provide the same with improved means for securing in place the teeth or prongs for cutting into or breaking the material being excavated. I preferably provide each of the side edges of the front wall with a longitudinally extending external flange 10 against which the edge of the side wall abuts, so that when the front and side walls are riveted together, as shown, the rivets will be relieved of shearing strains. The said digging or front wall is also provided with end flanges 11, 11 against which engage the ends of front and back reinforcing bands 12, 13, which are riveted to the side walls and the digging wall, the engagement of the bands with said flanges 11, 11, relieving the rivets of shearing strains. I preferably extend the sides of the digging wall up far enough at the sides of the bucket, as indicated in dotted lines in Fig. 1, so as to permit the pivoting of the bail on the rigid front wall construction and give added strength to the structure. I will now proceed to describe the improved means for interchangeably securing in place on the digging wall the digging teeth or prongs. I provide the front edge portion of the digging wall with a plurality of bosses or enlargements 14 spaced from each other in parallel relation and extending longitudinally of said digging wall, each of these bosses being provided with a longitudinally extending groove or channel 15, formed by parallel side walls or flanges 16, formed by the said boss or enlargement, the forward ends of said channels each opening through the front edge of the bucket, and the rear end terminating at a point short of the rear end of the boss or enlargement to provide a transverse bridge-piece 17 spaced from the plane of the bottom wall. The bottom of each channel 15 is closed by a transverse web 18 lying in the same plane as said digging wall, the forward edge of the web being cut away to provide recesses 19 extending inward from the front edge of the digging wall. At the rear end of the web 15, and beneath the bridge-piece 17, is an opening 20 through the bucket front wall. This opening is useful in cleaning out the space between the bridge-piece after casting, and also affords access by a tool to the rear

end of a tooth should the latter become jammed so as to render removal thereof difficult when replacement or repair of the tooth is necessary. The opening also provides clearance for the rear end of the tooth should the latter be torn loose from the front of the bucket and moved upward, as the rear end of the tooth may enter the said opening and prevent breakage of the bridge-piece. The rear end portions of the bosses 14 are curved from the rear end of the channel 15 downward and rearward toward the bottom of the bucket wall, and merge gradually into the latter so as to provide a smooth rounded surface in rear of the teeth, of such configuration as to obviate the clogging of material, such as earth, upon said bosses. 70 75 80

21 designates generally one of the teeth, the same consisting of a forward cutting portion 22, preferably of chisel form and provided with a rearward extending shank 23 adapted to be inserted in the channel 15 formed by the flanges of one of the bosses, said shank being provided preferably with parallel flat side faces 24 adapted to closely engage the inner parallel side faces of the flanges or walls of said channel, the upper face of the shank being so formed that, when it is in position in the channel, said face will form a continuation of the upper rear curved face of the rear portion of the boss 14 without projections or crevices to catch and hold the material. At its extreme rear end the shank of the tooth is provided with a locking projection 25, adapted to project under the bridge-piece 17, heretofore described, said shank having at the base of said locking projection a shoulder 26 to engage the front face of said bridge-piece, as clearly shown in Fig. 3. Upon its lower portion and at the base of the chisel head or cutting portion, the tooth is provided with a rearward projection 27, spaced from the under face of the shank to form a recess 28, which projection 27, when the tooth is assembled on the bucket, extends beneath the bottom wall, and said recess receives the front edge of the bucket, all as clearly shown in Fig. 3. The tooth shank is provided with a flat under face 30 which rests upon the web 18, heretofore described. It will be seen that, when the tooth is in assembled position, the locking projection 25 at the rear of the shank will prevent rocking of the tooth in one direction through the plane of the wall 6 while the engagement of the projection 27 and the recess 28 with the forward edge of the digging wall, will prevent rocking or movement in the opposite direction, so that the tooth will be securely held in position against dislodgment by any of the forces ordinarily operating to exert strains upon the tooth. Lateral movement of the teeth is prevented by the side flanges 16, as will be readily understood. In order to prevent 100 105 110 115 120 125 130

dislodgment of the tooth by movement longitudinally of itself and of the channel 15, I may insert a locking pin or rivet 31 through the shank of the tooth and the web 18 at the base of said channel 18, but it will be understood that the strains are sustained by the novel construction of the bucket wall, and that said pin or rivet may merely serve to prevent the tooth from slipping out of place. The outer side portions of the bosses constituting the side walls or flanges of the channels 15 are preferably concaved and reduced to substantially a sharp edge at their upper edges so as to in effect cause the portions of the bucket wall between the teeth, and the side faces of the teeth to be substantially coincident, and also provide a smooth rounded surface between adjacent pairs of flanges, and, therefore, obviate the existence of any projections or crevices which would be liable to receive and hold the dirt or other material being excavated.

I do not desire to be limited to the exact form of tooth shown as other forms of teeth may be employed without departing from my invention.

I desire it understood that I do not limit the application of my invention to excavating buckets of the type illustrated and described, as it is within the scope of my in-

vention to include all types of buckets in which the bucket digs or is filled by forcing a wall thereof into, through or under the material to be moved.

What I claim and desire to secure by Letters Patent of the United States is:—

1. A metallic digging bucket having the metal of its upper surface thickened at spaced points to form bosses extending longitudinally of the bucket from the front edge thereof, each boss being formed with an open channel merging into a socket having a top wall common with the boss, and a tooth located in each channel and having its end seated in said socket. 40

2. A digging bucket having a bottom wall provided with flanges extending longitudinally thereof inward from an edge of said wall, said flanges being joined at their inner portions by a bridge-piece, and a tooth located between said flanges and having a part held by said bridge-piece, and a shoulder engaging said bridge-piece. 50

In testimony whereof I have hereunto signed my name in the presence of two subscribing witnesses. 55

JOHN J. REHALLY.
